UNITED STATES PATENT OFFICE.

JUSTIN B. SHALER, OF NEW YORK, N. Y., ASSIGNOR OF ONE-HALF TO
WILLIAM J. O'HEARN, OF BROOKLYN, NEW YORK.

STEP-LADDER.

No. 821,834.

Specification of Letters Patent.

Patented May 29, 1906.

Application filed November 19, 1904. Serial No. 233,401.

To all whom it may concern:

Be it known that I, JUSTIN B. SHALER, a citizen of the United States, and a resident of Brooklyn, New York city, New York, have invented certain new and useful Improvements in Step-Ladders, of which the following is a specification.

My invention relates to step-ladders, and particularly to those provided with swinging rear supports, which may be folded either when the ladder is used resting against a wall or the like or when the ladder is not in use.

It comprises improvements in such supports, together with an improved shelf or pail-rest.

It further comprises details of construction, which will be specified and claimed.

Figure 1 is a perspective view of a step-ladder embodying my invention. Figs. 2 and 3 are respectively partial side and front elevations of the same on an enlarged scale. Figs. 4 and 5 show details.

1 designates the stair portion of a step-ladder comprising side risers 11 and treads 12. 25 Near their upper ends the risers 11 are pierced at 13 and are provided on their outer sides with plates 2, having apertures 21 registering with the apertures 13. The plates 2 are also provided, preferably at their lower ends, with laterally-extending flanges 22 23. 30 Passing through the apertures 13 and 21 is the horizontal bar 31 of the rear support 3. At the ends of the bar 31 are rigidly secured as 35 vertical members or side rods 32, shown as connected to the member 31 by ordinary L-joints 33. The lower ends of the rods 32, which in practice may be tubular, are threaded, as shown at 34. This enables them to engage with a rubber sleeve 35, as shown in Fig. 1, to prevent displacement on polished floors or with a flat shoe 36, (shown in Fig. 5,) which may be used, *e. g.*, on a grating. It will be noted that the entire rear support 3 is integral and pivoted, so that each bar 32 in 45 its operative position may swing out and engage with the flanges 22 of the side plates 2, as shown in full lines, Fig. 1, and in their non-operative position may lie adjacent the outer sides of the risers 11 and be held from forward movement by the flanges 23 on the plates.

To prevent the accidental disengagement of the support 3 from its operative position, I provide a rod or other obstacle engaged be-

tween the side of the riser 11 and the bar 32 55 near the apex of the angle made by them. As shown, the rod 4 is wound about the bar 31, as shown at 41, and held in position approximately against the inner sides of the risers 11 by means hereinafter described or 60 by any convenient manner. The lower end 42 of the rod 4 is laterally extended to engage between the riser 11 and the bar 32, as above set forth. The resiliency of the rod 4 enables the end 42 to be easily disengaged to permit 65 the swinging forward of the bars 32.

The extension or pail-shelf 5 may be pivotally supported in any convenient manner under any of the treads 12. As shown, it is under the upper tread and is pivoted on the 70 bar 31, its pivots 51 serving to maintain the coils 41 of the rod 4 in position. As shown, the rear edge of the tread 12 is provided with inwardly-extending bolts 52, engaging with eyes 53 on the shelf 5. By disengaging these 75 bolts the shelf may be turned on its pivots so as to hang adjacent the treads 12 and out of the way.

By the term "integral" as applied to the rear support of the step-ladder I of course include an inverted-U-shaped support made either in one piece or preferably in a plurality of pieces, as shown, so long as these are integrated or rigidly secured together to swing integrally. 85

It is evident that some parts of my invention may be used without others and that considerable mechanical changes may be made in various parts of the device without departing from my invention. 90

Having thus described my invention, what I claim, and desire to secure by Letters Patent, is—

1. A step-ladder comprising a stair portion consisting of side risers and treads, a rear support consisting of a horizontal connecting member and legs rigidly secured to said member at their upper ends and adapted to swing in line with and adjacent the outer side of said risers, and unitary means for pivotally attaching said rear support to said stair portion and for limiting their relative pivotal movement. 95

2. A step-ladder comprising a stair portion consisting of side risers and treads, a rear support composed of metal rods or tubes and comprising a horizontal connecting member and legs rigidly secured at their upper ends 100 105

to said connecting member and adapted to swing in line with and adjacent the outer side of said risers, and unitary means attached to said risers for engaging with the horizontal member of said rear support and for limiting its pivotal movement with respect to said stair portion.

3. A step-ladder comprising a stair portion consisting of side risers and treads, a rear support made from metal rods or tubing and comprising a connecting horizontal member and legs rigidly secured at their upper ends to said connecting member and adapted to swing in line with and adjacent the outer side of said risers, and side plates each pierced for pivotal engagement with the horizontal member of said rear support and provided with laterally-extending portions for limiting the pivotal movement of said support with respect to said stair portion.

4. A step-ladder comprising a stair portion consisting of side risers and treads, a rear support consisting of a horizontal pivotal member and legs rigidly secured thereto, and unitary means attached to said risers pierced to pivotally support the horizontal member of said rear support and provided with means for limiting the pivotal movement of the vertical members of said rear support with respect to said stair portion.

5. A step-ladder comprising a stair portion consisting of side risers and treads, a rear support consisting of a horizontal pivotal member and legs rigidly secured thereto, and side plates, one of which is attached to each of said risers near its upper end, is pierced to receive the horizontal member of said rear support and is provided with laterally-extending flanges adapted to limit the movement of one of the vertical members of said rear support in both directions.

6. A step-ladder comprising a stair portion consisting of side risers and treads, a rear support pivotally attached to said side risers, and means detachably engaged between said risers and the legs of said rear support approximately at the apex of the angle formed by said risers and the legs of said support for preventing the accidental dislodgment of said rear support.

7. A step-ladder comprising a stair portion consisting of side risers and treads, an in-

verted-U-shaped rear support, the horizontal member of which is pivoted in said risers, and a movable portion connected with said horizontal member and adapted to detachably engage between said risers and the legs of said rear support to prevent the accidental dislodgment of the latter.

8. A step-ladder comprising a stair portion consisting of side risers and treads, an inverted-U-shaped rear support, the horizontal member of which is pivoted in said risers, and a resilient rod secured on said horizontal member and having a laterally-extending portion adapted to engage between the leg of said support and one of said risers to prevent the accidental dislodgment of the support.

9. A step-ladder comprising a stair portion consisting of side risers and treads, a rear support composed of metal rods or tubes and comprising a horizontal member and legs rigidly secured to said horizontal member at their upper ends, said horizontal member extending between said risers adjacent their upper ends, a shelf pivotally attached to said horizontal member, and coöperating bolts and eyes common to the tread adjacent said horizontal member and to said shelf for detachably maintaining the latter in a horizontal position.

10. A step-ladder comprising a stair portion consisting of side risers and treads, a rear support including a horizontal member extending between said side risers adjacent their upper ends, a shelf pivotally attached to said horizontal member, coöperating bolts and eyes common to the tread adjacent said horizontal member and to said shelf for detachably maintaining the latter in a horizontal position, and a resilient rod secured on said horizontal member and having a laterally-extending portion adapted to engage between a leg of said rear support and one of said risers to prevent the accidental dislodgment of the support.

In testimony whereof I have signed this specification in the presence of two subscribing witnesses.

JUSTIN B. SHALER.
